UNITED STATES PATENT OFFICE.

MALCOLM OWEN, OF LONDON, ENGLAND.

PRINTING CYLINDER.

Application filed March 28, 1925. Serial No. 19,133.

To all whom it may concern:

Be it known that I, MALCOLM OWEN, a subject of the King of Great Britain, residing at 109 Farringdon Road, E. C. 1, London, England, have invented certain new and useful Improvements in Printing Cylinders, of which the following is a specification.

This invention relates to printing cylinders of the kind having a gap in which the ends of the printing sheet are fastened.

In fitting printing sheets to such cylinders, one end of the sheet (hereafter referred to as the "leading end") is anchored in the gap; the sheet is then wrapped around the cylinder and then the other end of the sheet (hereafter referred to as the "free end") is secured within the gap. A cylinder on which a sheet is fastened in this manner is described in patent specification No. 1,506,859.

The ends of the sheet having been fastened within the gap of the cylinder, a capping piece is disposed over the gap to cover the securing means, and if of the nature described in the said prior patent specification, substantially fills the gap.

A main object of the present invention is to provide a capping piece covering the means for securing the ends of the sheet within the gap, constructed so that when fixed in position, it completely fills the mouth of the gap, whereby a continuous cylindrical periphery to the cylinder is obtained. Another object is to provide means for securing both ends of the sheet within the gap, which is free to rock and adjust itself so as to compensate for any difference in length of the ends of the sheet within the gap.

A preferred construction of the present invention is illustrated by way of example in the accompanying drawings, in which:

Figs. 1, 2 and 3 are fragmentary sectional elevations through a printing cylinder of the kind having a gap illustrating successive steps employing the fixing means according to the present invention used in the fixing of a sheet on a cylinder;

Fig. 4 is a longitudinal elevation of a cylinder partly in section, the section being taken on a line corresponding to the line IV—IV of Fig. 3;

Fig. 5 is a fragmentary elevation of a capping piece included in the construction shown in Figs. 3 and 4;

Fig. 6 is a section on the line VI—VI of Fig. 5;

Figs. 7 and 8 are side elevation and plan respectively of the temporary fixing means for the leading end of the sheet shown in 60 use in Fig. 1; and

Figs. 9 and 10 are side elevation and plan respectively of a drag used for fixing both ends of the sheet within the cylinder gap, as indicated in Fig. 2.

Referring first to Figs. 1, 7 and 8 of the drawings, the leading end 5 of the sheet is temporarily secured within the cylinder gap by hook members 35; conveniently two hook members only are utilized, one at each third 70 of the distance along the gap being found preferable. Each of the hook members is secured to a bed plate 10 by a fixing screw 37, and each comprises a lug 36 engaging into slots previously formed in the end 5 of 75 the printing sheet. These lugs 36 hook into the said slots, securely holding the leading end of the sheet within the cylinder gap, while the sheet is being wrapped around the cylinder. When the sheet has been wrapped 80 around the cylinder and the free end 4 is also within the gap, as illustrated in Fig. 2, drags 38 are utilized. These drags are in the form of a plate, as clearly indicated in Figs. 9 and 10, each plate including a lug 85 39 and a lug 40. The lugs 39 hook into slots in the leading end 5 of the sheet and the lugs 40 hook into slots in the free end 4 thereof, both ends of the sheet being slotted for the reception of the lugs 39 and 40 before being applied to the cylinder.

The drags are secured to the bed plate 10 by fixing screws 41, the bed plate having a series of borings for the reception of the screws 41 and 37. As the screws 37 and 41 are 95 similar the screws 41 can subsequently be substituted in the borings taken up by the screws 37 holding the temporary hook members 35.

Having secured both ends of the sheet within the gap by a plurality of drags 38 and the two hook members 35, the latter are removed and substituted by drags. (In Fig. 3 the dot and pick lines indicate the hook members.) Both ends of the sheet will then be secured by a plurality of drags, 100 for example nine, as shown in Fig. 4.

A particular feature of the means for securing each drag to the bed of the gap is that a pivotal connection is provided between the drags and their respective securing 110

means. To this end each drag plate is formed with a cup on its upper surface, as indicated at 42 in Figs. 2, 9 and 10, and a convex underside 43 to the head of each fixing screw 41 is formed to correspond to the cupping on the drag so as to ride smoothly therein, the drag plate being bored so as to provide a clearance around the fixing screw 41 and permit desired play between them if there is a relative motion between the drag and the head of the screw during fixing the ends of the sheet, due to one end being longer than the other within the gap of the cylinder. This arrangement, in nature a floating anchorage for the ends of the printing sheet, therefore permits the drag member to rock freely and thereby compensate for any difference in the length of the ends of the sheet within the gap.

In order to fill up the mouth of the gap and cover the drags a single capping piece is employed. It will be noted that the walls of the gap incline towards each other and give the gap a tapered form. Accordingly, the capping piece also is of tapered form corresponding to the shape of the gap.

The capping piece rests on the bed plate 10 and is provided with arches 44 on its underside which bridge over all the drags so as not to interfere with their function, and is fixed in position by screws 45 which engage into tappings made in the bed plate 10 between the tappings for the reception of the fixing screws 41 of the drags. The top part of the capping piece is of convex form conforming with the radius of the cylinder and is bored at intervals from the top radially of the cylinder for the reception of its screws 45, the borings being such as to deeply countersink the heads of the fixing screws and extending at a reduced diameter from the seating of the screw heads to the gap for the reception of the shanks of the fixing screws. Each side of the capping piece is rabbeted, as indicated at 46, for the reception of compressible packing strips, termed laces, indicated at 47, which provide continuity between the periphery of the cylinder and the convex face of the capping piece. As indicated, each rabbeted portion of the capping piece of the undercut form, that is, so that the innermost part is of greater depth than that at the periphery of the cylinder. With such an arrangement the compressible packing strips are also of tapered form, so that as the capping piece is drawn into the gap the laces are wedged into position, and any outstanding or proud portions can be trimmed off.

Each side of the gap near the periphery of the cylinder, that is, at the mouth of the gap, is preferably recessed, as indicated at 50, the recesses being disposed so as to be partly overlapped by the rabbets for the purpose of allowing a little give in the sheet

to permit lateral spreading of the laces, when the capping piece with the laces is introduced, thereby assuring retention of the compressible packing strips during printing operations.

Both the constructions hereinbefore described provide for lodging the compressible packing strips between the sides of the capping piece and the walls of the gap, the nature of the lodgement being such that as the capping piece is drawn into position by its fixing screws, the strips are compressed between the sides of the capping piece and the walls of the gap, and a continuous cylindrical periphery of the cylinder is thereby obtained.

In order that the borings receiving the heads of the fixing screws 45 shall not disturb the continuity of the outer surface of the cylinder, the space between the head of the bolt and the convex face of the capping piece is filled with a plug 48 of suitable material, such as compressed fibre, the part of the boring above the head of the screws 45 being tapped, and the plug being externally threaded to be screwed into position, the plug having two recesses 49 (Fig. 3), in which the pins of a pin spanner may engage. Both the screws 37 and 41 may have a convex slot, as clearly indicated in the screws 41 in Fig. 2, so as to provide ample room for a key spanner to turn these members within the gap.

In the construction herein described the use of a bed plate 10 is referred to. Obviously the actual bed of the gap may be bored to receive the several fixing screws and the term "fixed to the bed of the gap" used in the present specification is intended to cover such construction.

In utilizing hook members 35 and drags 38 as hereinbefore described a novel method of securing the ends of a printing sheet within the gap of the cylinder is obtained which consists in temporarily anchoring the leading end and drawing the free end into the gap by drag members which engage both ends of the sheet, the drag members being mounted to compensate for any difference of length of the ends of the sheet within the gap as they are secured to the bed of the gap, the temporary means aforesaid being then removed and individual drag members substituted therefor.

I claim:

1. A printing cylinder having a gap, means for securing within the gap the ends of a sheet when wrapped around the cylinder, a capping piece disposed over the securing means to substantially fill the gap, compressible packing strips lodged between each side of the capping piece and the walls of the gap, and means for securing said capping piece in said gap operating to draw the capping piece into the gap whereon the

packing strips are compressed between the sides of the capping piece and the walls of the gap, and a continuous cylindrical periphery for the cylinder thereby obtained.

- 5 2. A printing cylinder having a gap, means for securing within the gap the ends of a sheet when wrapped around the cylinder, a capping piece disposable over the securing means to substantially fill the gap, 70
 10 said capping piece including rabbeted sides, compressible packing strips arranged in said rabbets, and means for securing said capping piece in said gap operating to draw the capping piece into the gap, whereon the 75
 15 packing strips are compressed between the sides of the capping piece and the walls of the gap, and a continuous cylindrical periphery for the cylinder thereby obtained. 80

3. A printing cylinder having a gap, 85
 20 the walls of which incline towards each other to give the gap a tapered form, means for securing within the gap the ends of a sheet when wrapped around the cylinder, a capping piece of tapered form corresponding 90
 25 to the shape of the gap, disposed over the capping piece to substantially fill the gap, rabbets on the sides of the capping piece, compressible packing strips arranged in the rabbets, and means for securing said capping 95
 30 piece in said gap operating to draw the capping piece into the gap, whereon the packing strips are compressed between the sides of the capping piece and the walls of the gap, and a continuous cylindrical periphery for the cylinder thereby obtained. 100

4. A printing cylinder having a gap, the walls of which incline towards each other to give the gap a tapered form, means for securing within the gap the ends of a sheet 105
 40 when wrapped around the cylinder, a capping piece of tapered form corresponding to the shape of the gap, disposed over the capping piece to substantially fill the gap, undercut rabbets on the sides of the capping 110
 45 piece formed so that the innermost part is of greater depth than that at the periphery of the cylinder, tapered compressible packing strips arranged in the rabbets, and means for securing said capping piece in 115
 50 said gap operating to draw the capping piece into the gap, whereon the packing strips are wedged up and compressed between the sides of the capping piece and the walls of the gap, and a continuous cylindrical periphery for the cylinder thereby obtained. 120

5. A printing cylinder having a gap, the walls of which incline towards each other to give the gap a tapered form and are each recessed near the mouth of the gap, means for securing within the gap the ends of a sheet 125
 60 when wrapped around the cylinder, a capping piece of tapered form corresponding to the shape of the gap, disposed over the capping piece to substantially fill the 130
 65 the capping piece to substantially fill the

gap, undercut rabbets on the sides of the capping piece partly overlapping the recesses in the walls of the gap and formed so that the innermost part is of greater depth than that at the periphery of the cylinder, tapered compressible packing strips arranged in the rabbets, and means for securing said capping piece in said gap operating to draw the capping piece into the gap, whereon the packing strips are wedged up and compressed between the sides of the capping piece and the walls of the gap, and a continuous cylindrical periphery for the cylinder thereby obtained, the sheet being permitted to yield over the said recesses, thereby allowing lateral spreading of the packings which assures their retention during printing operations.

6. A printing cylinder having a gap, the walls of which incline towards each other to give the gap a tapered form and are each recessed near the mouth of the gap, means for securing within the gap the ends of a sheet when wrapped around the cylinder, a capping piece of tapered form corresponding to the shape of the gap disposed over the capping piece to substantially fill the gap, undercut rabbets on the sides of the capping piece partly overlapping the recesses in the walls of the gap and formed so that the innermost part is of greater depth than that at the periphery of the cylinder, tapered compressible packing strips arranged in the rabbets, said capping piece being bored at intervals from the top radially to the cylinder to deeply countersink heads of fixing screws, each boring extending at a reduced diameter through the capping piece for the reception of the shanks of the fixing screws, which enter the bed of the gap, and plugs screwing snugly into the first mentioned borings to cover the countersunk screw heads and complete the cylindrical periphery of the cylinder.

7. A printing cylinder having a gap, a plurality of drags disposable in the gap formed to hook into each slotted end therein of a sheet wrapped around the cylinder, means for securing each drag to the bed of the gap providing a pivotal connection between the drags and securing means, whereby each drag member is free to rock and thereby compensate for any difference in the length of the ends of a sheet within the gap, a capping piece disposed over the drags to substantially fill the gap, compressible packing strips lodged between each side of the capping piece and the walls of the gap, and means for securing said capping piece in said gap operating to draw the capping piece into the gap whereon the packing strips are compressed between the sides of the capping piece and the walls of the gap, and a continuous cylindrical periphery for the cylinder thereby obtained.

8. A printing cylinder having a gap, a plurality of drags disposable in the gap formed to hook into each slotted end therein of a sheet wrapped around the cylinder,
5 a cup in the upper face of each drag, a screw for securing each drag to the bed of the cylinder, a convex underside to the head of the screw formed to correspond to the cupping on the drag, a capping piece disposed over
10 the drags to substantially fill the gap, compressible packing strips lodged between each side of the capping piece and the walls of the gap, and means for securing said capping piece in said gap operating to draw
15 the capping piece into the gap whereon the packing strips are compressed between the sides of the capping piece and the walls of the gap, and a continuous cylindrical periphery for the cylinder thereby obtained.

9. A printing cylinder having a gap, a

plurality of drags disposable in the gap formed to hook into each slotted end therein of a sheet wrapped around the cylinder, means for securing each drag to the bed of the gap providing a pivotal connection between the drags and securing means, whereby each drag member is free to rock and thereby compensate for any difference in the length of the ends of a sheet within the gap.

10. A printing cylinder having a gap, a plurality of drags disposable on the gap formed to hook into each slotted end therein of a sheet wrapped around the cylinder, a
25 cup in the upper face of each drag, a screw for securing each drag to the bed of the cylinder, a convex underside to the head of the screw formed to correspond to the cupping on the drag.

In testimony whereof I affix my signature.

MALCOLM OWEN.
